(57) **CLAIM**

We claim the ornamental design for a remote control, as shown and described.

DESCRIPTION

FIG. 1 is a front perspective view of a remote control; FIG. 2 is a top view of the remote control shown in FIG. 1; FIG. 3 is a front elevation view of the remote control shown in FIG. 1; FIG. 4 is a rear elevation view of the remote control shown in FIG. 1; and, FIG. 5 is a side elevation view of the remote control shown in FIG. 1.

The ornamental design which is claimed is shown in solid lines in the drawings. The broken lines in the drawings are for illustrative purposes only and form no part of the claimed design.
